UNITED STATES PATENT OFFICE.

EDMUND E. CLOSE, OF BROCKTON, MASSACHUSETTS, ASSIGNOR, BY DIRECT AND MESNE ASSIGNMENTS, OF ONE-HALF TO ADELBERT L. SEWALL AND ONE-HALF TO CHARLES R. FELTON, BOTH OF BROCKTON, MASSACHUSETTS.

SCALING-LADDER.

1,205,594.

Specification of Letters Patent. Patented Nov. 21, 1916.

Application filed November 22, 1915. Serial No. 62,741.

To all whom it may concern:

Be it known that I, EDMUND E. CLOSE, a citizen of the United States, residing at Brockton, in the county of Plymouth and 5 State of Massachusetts, have invented an Improvement in Scaling-Ladders, of which the following is a specification.

This invention relates to certain improvements in scaling ladders and more particularly to means for mounting thereon, the supporting hooks, with which such ladders are usually provided, so that they may be folded flat with the ladder when not in use.

Some of the chief objections to the forms 10 of folding hooks which have been previously employed are that, when the hooks were unfolded, or set in position for use, they were liable to be moved back to folded position, while the ladder was being raised, 15 and this arrangement was further objectionable on account of the time required in setting the hooks in position for use.

The object of my invention is to provide 20 means for mounting a pair of supporting hooks on a ladder, which will enable the hooks to be locked in folded position, and to be unlocked and automatically moved to position for use, where they will be held against accidental displacement.

30 I accomplish these objects by the means shown in the accompanying drawings, in which;—

Figure 1 is a front elevation of the upper 35 end-portion of a ladder, provided with an embodiment of my invention. Figs. 2 and 3 are side elevations of the inner portion of one side of the ladder, showing certain parts in different positions. Fig. 4 is a top plan view, with the parts in the position of Fig. 40 1. Figs. 5, 6, 7, and 8 are detail views, on an enlarged scale, of the means for supporting, locking, and operating one of the hooks. Fig. 9 is a similar view of the means employed in connection with the other hook. 45 Fig. 10 is a sectional view on the line 10—10 of Fig. 8.

In the drawings, α and α' indicate the side 50 strips of an ordinary ladder which are connected by the usual rungs b . The side strip α has an oblong casing c mounted on the inner side thereof, adjacent its end, and one of the supporting hooks d extend therethrough, and the other side strip α' , also has a similarly mounted and formed casing e

thereon, and through which the other supporting hook f extends, the shank portions d' and f' of said hooks extending parallel to the side strips and being adapted to move rotatably and also to slide longitudinally in their respective supporting casings. 55

Projecting pins d^2 and f^2 are respectively supported in collars d^3 and f^3 , which are mounted on the shanks d' and f' respectively, and coil springs g and h are, respectively, arranged about said shanks, between the bottom of the casings c and e , and said collars d^3 and f^3 , respectively. Sleeves i and j are mounted in the casings c and e respectively, in position to receive the shanks d' , f' , said sleeves being respectively provided with slots i' and j' , into which the corresponding pins d^2 and f^2 extend, said slots extending upward from approximately the same level in each sleeve, in an oblique direction, about the sleeve, for approximately 90°, and then longitudinally, 60 as best shown in Figs. 5, 8, and 9. It is to be noted that the slot i' extends about the sleeve to the right, and that the slot f' extends to the left, in the oblique portions 65 thereof. The slot i' is also extended beyond the lower end of its oblique portion, for a short distance and in a direction longitudinally of the sleeve, as best shown in Figs. 7 and 8. The arrangement of said slots i' and j' is such that, when the pins d^2 and f^2 are 70 in the upper ends thereof, the hooks d and f will be held in approximately parallel planes or in positions approximately at right angles to the plane of the ladder, as 75 shown by dotted lines in Fig. 1, and in Fig. 3, so that, when the hooks are pushed downwardly, they will also be swung toward each other, by the engagement of the pins d^2 , f^2 , with the oblique portions of the slots, said 80 hooks thus being swung through an arc of 90°, so that they lie flat or approximately in the plane of the ladder. Said hooks also 85 are so arranged that the hook d is swung into the path of the hook f when they are 90 moved to the folded position, as shown in 95 Figs. 1 and 4.

A latch m is mounted in the casing c upon a pivot n , in position to engage the pin d^2 , when it is moved down into the lower portion of the slot i' , and an operating rod o is connected to the latch m by a pivot pin p and is extended through the bottom of the 100 105

casing for a suitable distance over the rungs and along the side strip a , preferably to the foot of the ladder. A spring r is mounted on the rod o between a collar o' thereof and the bottom of the casing c , said spring acting to hold the hook m normally in the position of Fig. 7. The end portion of the hook m is beveled on its upper side, so that, when the pin d^2 is pressed down into the lower portion of the slot, the latch will be pushed back to the dotted position of Fig. 8, the latch being returned to locking position by spring r .

When the hooks d and f are in the unfolded position of Fig. 3, the collars d^3 , f^3 , will be held against the upper ends of the casings c and e , and when in this position, the pins d^2 and f^2 will be held in the upper ends of the slots i' and j' , the sides of which will engage said pins and hold the hooks against swinging movement. If it is desired to move the hooks to folded position, the hook f is first pushed downward against the action of its spring h , and, as it is pushed downward, the pin f^2 thereon will engage the inclined portion of slot j' and cause the hook to be swung inwardly, so that it lies flat with the ladder by the time the pin reaches the lower end of the slot. Then the other hook d is pushed downwardly in the same manner and is likewise caused to swing inwardly, toward the hook f until its end portion engages the same, and then it is pushed still farther, so that its pin d^2 passes into the lower end portion of the slot i' and pushes aside the latch m , until the latter is permitted to engage the pin and prevent the spring g from forcing the hook d outwardly. Both hooks will then be locked in the folded position, as the hook d , which is locked by the latch m , will prevent the hook f from being swung outward by spring h . When it is desired to use the hooks, the rod r is pulled down, so that the latch m is thrown out of engagement with the pin d^2 , permitting spring g to force the hook d up until its collar d^3 engages the top of the casing c , the sides of the cam slot i , causing it, at the same time, to be rotated to the position at right angles to the ladder. As the hook d is swung outwardly, it will immediately release the hook f , so that its spring h will move it upward and swing it outward until it is returned to the unfolded position.

While each hook is held against swinging movement when in unfolded position, by the pins d^2 and f^2 , which engage the longitudinally extending upper portions of the slots i' and j' , if, by accident, either hook should be pushed inwardly and swung laterally, as soon as it was released, it would be again returned to its position for use.

The above-described construction not only enables the hooks to be securely held in

either folded or unfolded position, but also enables them to be readily moved from one position to the other, and to be unfolded after the ladder has been raised into the position in which it is to be used.

I claim:

1. In combination with a ladder, a pair of hooks mounted thereon, means tending to move said hooks from a folded to an unfolded position, one of said hooks having a locking device for holding it in folded position, and the other hook being relatively associated therewith to be locked in folded position by the aforesaid hook.

2. In combination with a ladder, a pair of hooks mounted thereon, means tending to move said hooks from a folded to an unfolded position, one of said hooks having a locking device for holding it in folded position, and for releasing it, to permit it to move to unfolded position, and the other hook being relatively associated therewith to be locked in folded position by the aforesaid hook, and to be released thereby, to permit both hooks to move, simultaneously, to unfolded positions, when the locking device is moved to releasing position.

3. In combination with a ladder, a pair of hooks mounted thereon and each separately spring-actuated to move from folded to unfolded positions, one of said hooks having a locking device for holding it in folded position, said locking device being movable to permit the hook to move to unfolded position, and the other hook being arranged to be engaged by and locked in folded position by the aforesaid hook, when the latter is in its folded position, to permit simultaneous release of said hooks by said locking device.

4. In combination with a ladder, a hook mounted thereon to swing between a folded position, in which it lies flat with the ladder, and an unfolded position in which it projects therefrom, means normally actuated to swing said hook from folded to unfolded position, and a locking device for holding the hook in folded position, and movable to release the hook to permit it to be moved to unfolded position.

5. In combination with a ladder, a hook mounted thereon to swing between a folded position, in which it lies flat with the ladder, and an unfolded position in which it projects therefrom, spring-actuated means arranged to swing the hook from folded to unfolded position, a latch arranged to lock the hook when moved to folded position, and means to operate the latch to release the hook.

6. In combination with a ladder, a hook mounted thereon to swing on its shank about an axis extending longitudinally of the ladder between a folded position, in which the hook lies flat with the ladder,

and an unfolded position in which it lies perpendicularly thereto, means to lock the hook in folded position, actuating means arranged to move the hook to unfolded position when released, and engaging means to hold the hook against swinging movement when in unfolded position.

7. In combination with a ladder, a hook having its shank mounted thereon to slide longitudinally and move rotatably, a spring arranged to engage the shank to move the same longitudinally, and guiding means to swing the hook from folded to unfolded position, as it is moved by the spring.
- 10 8. In combination with a ladder, a hook

having its shank mounted thereon to slide longitudinally and move rotatably, a spring arranged to engage the shank to move the same longitudinally, a casing having a cam slot therein extending longitudinally and 20 circularly of the shank, and a projection on the shank to engage in said slot and cause a partial rotation of the shank as it is moved by said spring.

In testimony whereof, I have signed my name to this specification.

EDMUND E. CLOSE.
